ABSTRACT OF THE DISCLOSURE

Process for producing vinyl acetate which comprises subjecting a feedstock consisting essentially of ethylene glycol diacetate to pyrolysis in the vapor phase at a mass velocity in excess of 200 lbs./hr./ft.² of pyrolysis zone cross-sectional area.

CROSS-REFERENCE TO RELATED APPLICATION

This application is a continuation-in-part of co-pending application Ser. No. 83,221, filed Oct. 22, 1970, now abandoned.

BACKGROUND OF THE INVENTION

Vinyl acetate is a large-scale article of commerce having wide applicability in the production of polymeric compounds. Traditionally, vinyl acetate has been prepared by the reaction between acetylene and acetic acid. More recently, the reaction of ethylene, oxygen and acetic acid has been used. Both these processes, however, suffer from disadvantages. Acetylene is an expensive raw material and also is hazardous to handle. The ethylene-based processes involve oxidations which are relatively difficult to operate safely; and, in some instances, have suffered from serious corrosion problems.

Among other alternate routes to vinyl acetate considered in the prior art, one offering substantial promise employs ethylene glycol diacetate as the feed. However, prior art attempts to pyrolyze (i.e., thermally crack) this material to vinyl acetate have not found acceptance because of low selectivities. Thus, for example, while Chitwood, U.S. Pat. No. 2,251,983 proposed to produce vinyl acetate by such a pyrolysis in 1941, the selectivities obtained were under 70%, a value too low to make the process economically viable. More recent work (see Shibahara, Yoshijima and Tsutsumi, Technol. Reports, Osaka University, 11, No. 482 (1961), p. 405) failed to demonstrate significantly increased selectivity; indeed, the results reported in this relatively recent work were in large measure inferior to Chitwood's earlier work and in only one isolated experiment was a selectivity of even 80% obtained. The prior art, therefore, would seem to indicate that an economically viable process for the production of vinyl acetate by pyrolysis of ethylene glycol diacetate would not be practicable because yields resulting from such pyrolysis were relatively low.

SUMMARY OF THE INVENTION

It has, however, now been found that selectivities in ethylene glycol diacetate pyrolysis to vinyl acetate of 80–90% and even higher are readily obtained when the feedstock is subjected to vapor phase pyrolysis in a pyrolysis zone at a feedstock mass velocity in excess of 200 lbs./hr.ft.² of pyrolysis zone cross-sectional area. It has also been found that best yields across the pyrolysis zone are obtained when the time-temperature characteristics of the pyrolysis are carefully controlled, although good yields can be obtained even when the pyrolysis occurs under other time-temperature conditions. In practice, the feedstock is forced through the pyrolysis zone by means

2

of a pressure gradient, i.e., a pressure differential between pyrolysis zone inlet pressure and pyrolysis zone outlet pressure. In preferred practice, external heat (i.e., heat from an external source) is supplied to the materials being pyrolyzed during the pyrolysis. This requires that the surface of the pyrolysis zone in contact with the material being forced through the pyrolysis zone (feedstock, reaction products and reaction diluents, if any) be maintained at a higher temperature than the bulk temperature of the material flowing through the pyrolysis zone to provide the thermal gradient necessary for the heat input. Preferably, though not essentially, the temperature of the surface in contact with the material flowing through the pyrolysis zone (the "skin temperature") is controlled so as not to exceed the bulk temperature by more than 25° C.

DETAILED DESCRIPTION OF THE INVENTION

The process of this invention involves the vapor phase pyrolysis of a feedstock consisting essentially of ethylene glycol diacetate to vinyl acetate. In the pyrolysis the ethylene glycol diacetate is converted to a mixture containing, in addition to unconverted ethylene glycol diacetate, vinyl acetate, acetic acid and, of course, some by-products.

The source of the ethylene glycol diacetate is not of substantial importance to this invention, and it can be prepared, for example, by routine esterification of ethylene glycol with acetic acid. However, a preferred manner for preparing this material is by the reaction of ethylene, oxygen and acetic acid in the presence of a halogen or halogen compound in conjunction with a variable valence metal cation such as tellurium, manganese, copper, cobalt and chromium, which metals can be supplied as such or in the form of their salts. The preferred process for preparation of ethylene glycol diacetate is more fully described in Belgian Pat. No. 733,104, which issued on Mar. 2, 1970.

Preparation of the ethylene glycol diacetate feedstock in this manner, however, provides a material for pyrolysis which often can contain, even after purification, some quantity, typically 20% (mole basis) or less of ethylene glycol monoacetate, ethylene glycol, diethylene glycol, and diethylene glycol diacetate and monoacetate, as well as smaller amounts (up to 1,000–2,000 p.p.m. (weight basis)) of halogenated impurities such as halohydrin, ethylene dihalide, ethylene haloacetate, diethylene glycol monohalide and diethylene glycol haloacetate. All of the foregoing impurities are permissible components in the ethylene glycol diacetate feed to pyrolysis, and it is for this reason that the feedstock to the pyrolysis is described as one "consisting essentially of" ethylene glycol diacetate. It should be noted, however, that these impurities, during pyrolysis, can yield some vinyl acetate but their selectivities to vinyl acetate in such pyrolysis are very much lower than that observed with ethylene glycol diacetate itself.

Additionally, it is particularly preferred to employ feedstock containing the minimum practicable amount of halogenated materials since the halogenated materials introduced not only create corrosion problems but also appear to somewhat reduce the overall selectivity to vinyl acetate in the pyrolysis. Accordingly, while it is permissible to employ feedstock to pyrolysis containing 1,000–2,000 p.p.m. of halogenated impurities, it is generally more desirable to employ feeds containing under 100–200 p.p.m. of such impurities, and it is preferred to employ feedstocks containing 10–20 p.p.m. of such halogenated impurities or even less.

Moreover, in continuous commercial operation, the pyrolysis would normally be carried out on a partial conversion basis, i.e., only from about 5% to about 60% of the ethylene glycol diacetate will be converted per pass

through the pyrolysis zone and unconverted material, together with by-products unavoidably formed during previous passes of the feedstock through the pyrolysis zone, would be recycled. Such byproducts can thereby build up in the feedstock to an appreciable extent and, even though purged in part, can accumulate to a point amounting to as much as 10% (mole basis) of the total feed. Such by-products that can build up in this manner include additional ethylene glycol monoacetate, acetone, acetaldehyde, acetic anhydride, ketene, ethylidene diacetate and high-boiling materials of unknown structural formulae.

Finally, it should also be recognized that ethylene glycol diacetate is a high-boiling liquid which requires high temperature or low pressure or both to be readily volatilized. To assist in such volatilization, it is often advantageous to introduce low-boiling materials during vaporization and prior to pyrolysis. Any material which is relatively inert under pyrolysis zone conditions can be used for this purpose. These materials include gases such as nitrogen, argon, helium and carbon dioxide, as well as light paraffins such as methane, ethane, propane and butanes. Also suitable and preferred as a diluent is acetic acid since it does not introduce any extraneous material to the system. Acetic acid is substantially inert under pyrolysis zone conditions except that it may undergo partial dehydration to acetic anhydride; such dehydration is not in any way deleterious to the overall process. Whichever inert (including, in this context, acetic acid) is employed, it can be employed in amounts as little as 0.5-1.0 mole percent and up to amounts as great as 70-80 mole percent. It is normally desired to employ amounts of inert from about 1% to about 60% to facilitate ethylene glycol diacetate volatilization, and it is preferred to employ inerts in an amount between about 3% and about 50%, all these percentages being on a mole basis.

Despite the presence of the wide variety of material in the feedstock to the pyrolysis as outlined on the preceding paragraphs, the feedstock is nevertheless characterized as one consisting essentially of ethylene glycol diacetate since it is this material which undergoes highly selective pyrolysis to vinyl acetate and, except as hereinabove noted, these other materials display no adverse effect upon the pyrolysis and, in some instances, are indeed favorable to the pyrolysis. In normal practice one would use feedstocks containing (exclusive of light diluents added to facilitate volatilization) 50-100% (mole basis), desirably 75-100% (mole basis) and preferably 80-100% (mole basis) of ethylene glycol diacetate.

As hereinabove indicated, the critical feature associated with obtaining high selectivities in the conversion of ethylene glycol diacetate to vinyl acetate by pyrolysis is the mass velocity (computed on the basis of contained ethylene glycol diacetate) within the pyrolysis zone. With the mass velocity in excess of 200 lbs./hr./ft.² of pyrolysis zone cross-sectional area, selectivities in the pyrolysis are substantially improved over those obtainable at lower mass velocities. Further, it has been observed that, within broad limits, the higher the mass velocity, generally the better will be the selectivity up to a mass velocity of about 1,000 lbs./hr./ft.² of pyrolysis zone cross-sectional area. Beyond this point further improvements in selectivity are seemingly minor. Accordingly, while any mass velocity in excess of about 200 lbs./hr./ft.² of pyrolysis zone cross-sectional area is operative and within the scope of this invention, it is normally desired to operate with mass velocities in excess of 250 lbs./hr./ft.² of pyrolysis zone cross-sectional area, and it is preferred to operate with mass velocities in excess of 300 lbs./hr./ft.² of pyrolysis zone cross-sectional area.

The upper limit of mass velocity employable within the pyrolysis zone, on the other hand, is not associated with factors directly related to selectivity. As those skilled in the art will realize, the higher the mass velocity within the pyrolysis zone, the higher will be the pressure drop

across the pyrolysis zone, i.e., the greater will be the pressure gradient referred to above. As a consequence, the higher the pressure drop, the higher the inlet pressure will be and the higher the pressure that the equipment within the pyrolysis zone must be designed to withstand. The consequences of higher design pressures on equipment cost and operating cost is manifest; thus, the primary factor affecting the upper limit of mass velocity is an economic one. A somewhat less important but related factor associated with extremely high mass velocities is that the higher the mass velocity, the higher will be the temperature needed or the greater will be the amount of inert diluent needed to vaporize the ethylene glycol diacetate-containing feedstock (the alternative of providing compression facilities is feasible but costly). Accordingly, economic conditions would normally dictate the use of mass velocities through the pyrolysis zone which are less than about 500,000 lbs./hr./ft.² of pyrolysis zone cross-sectional area, desirably less than 300,000 lbs./hr./ft.² of pyrolysis zone cross-sectional area and preferably less than 200,000 lbs./hr./ft.² of pyrolysis zone cross-sectional area.

Other conditions within the pyrolysis zone are conventional. Thus, for example, pyrolysis temperatures between about 435° C. and about 560° C. and preferably between about 445° C. and about 550° C. are employed. Residence times within the pyrolysis zone between about 0.10 and about 200 seconds, preferably between about one second and 100 seconds are employed. Residence times within the pyrolysis zone, as used throughout this specification and claims, are determined at the arithmetic average of inlet and outlet pyrolysis zone temperature and pressure and are determined on the basis of feedstock without consideration of increase in the number of moles of gas flowing (and hence in gas velocity) as the feedstock is pyrolyzed. It should also be noted that the feedstock to the pyrolysis zone would normally be subjected to one or more preheating stages prior to pyrolysis, for example, by indirect heat exchange first with steam or hot oil and/or by indirect heat exchange with pyrolysis zone effluent. The residence times of the feedstock within such preheat equipment is not part of the residence time within the pyrolysis zone as this phrase is herein used.

Although the vapor phase pyrolysis reaction is accompanied by an increase in volume (i.e., one mole of ethylene glycol diacetate, on pyrolysis, theoretically yields one mole of vinyl acetate plus one mole of acetic acid) pyrolysis zone pressure is not a major factor affecting selectivity. Thus, suitable pyrolysis pressures can be sub-atmospheric, atmospheric, or super-atmospheric, and pressures of from about 0.1 p.s.i.a. up to 115 p.s.i.a. or even higher can readily be employed. When pyrolysis zone pressures higher than about 115 p.s.i.a. are employed, it is normally preferred to dilute the ethylene glycol diacetate-containing feedstock with a diluent (preferably acetic acid) to reduce the partial pressure of ethylene glycol diacetate within the pyrolysis zone to a value less than 115 p.s.i.a. Additionally, operation of the pyrolysis zone with sub-atmospheric outlet pressures is less preferable than operation with higher outlet pressures because equipment designed for sub-atmospheric pressure operation tends to be more expensive. Accordingly, it is generally desired to operate with pyrolysis zone pressures between about atmospheric and about 115 p.s.i.a., preferably between about 0.5 p.s.i.g. and about 80 p.s.i.g. Additionally, to maximize ease of equipment design, it is preferred to so configure the pyrolysis zone such that the pressure drop thereacross (i.e., the pressure gradient or fluid driving force) is between 0.5 p.s.i. and about 65 p.s.i., preferably between about 0.5 p.s.i. and about 25 p.s.i.

Also as hereinabove indicated, it has been found that highest selectivities in the pyrolysis of ethylene glycol diacetate to vinyl acetate are obtained when the time-temperature characteristics of the pyrolysis zone are care-

fully controlled within specific limits. These limits are most readily defined in terms of a series of equations interrelating residence time and pyrolysis zone temperature. Thus, residence time preferably is not less than a value such that

$$(1) \quad \ln \theta = \frac{27,940}{T} - 35.8273$$

and preferably is not in excess of a value such that

$$(2) \quad \ln \theta = \frac{25,000}{T} - 28.8175$$

In an especially preferred mode of operation, the residence time is not less than a value such that

$$(3) \quad \ln \theta = \frac{25,000}{T} - 31.7002$$

and preferably is not in excess of a value such that

$$(4) \quad \ln \theta = \frac{25,000}{T} - 29.0945$$

In all of the foregoing equations, $\ln$ is the symbol for the Napierian or natural logarithm, θ is the residence time of the feedstock within the pyrolysis zone in seconds and T represents the arithmetic average of inlet and outlet pyrolysis zone temperatures expressed in degrees Kelvin. In the preferred time-temperature regime of operation, defined by Equation 1 and 2 above, the value for θ is 200 seconds or less, while T is at least 708° K. (435° C.) but is not greater than 833° K. (560° C.). In the especially preferred time-temperature regime of operation defined by Equation 3 and 4 above, θ is restricted to a value of 100 seconds or less, while T is at least 718° K. (445° C.) but not above 823° K. (550° C.).

The annexed drawing, consisting of a single figure, graphically reproduces the time-temperature relationships set forth in the form of equations in the preceding paragraph. In this graphic representation, the ordinate, plotted on a logarithmic scale, is the residence time (θ) expressed in seconds, while the abscissa is the arithmetic average of pyrolysis zone inlet and outlet temperatures (expressed in degrees Kelvin) and thus corresponds to T in the foregoing equations. The larger area in the annexed drawing, denoted by reference letters B-C-D-E-F, represents the preferred regime of controlled time-temperature characteristics defined by Equations 1 and 2 above. The smaller area in the annexed drawing, denoted by reference letters G-H-J-K-L, represents the especially preferred mode of operations defined by Equations 3 and 4 above.

Control of the time-temperature characteristics within the limits prescribed by the foregoing equations is readily accomplished. For example, given an existing pyrolysis zone operating at given temperatures and residence times, one can compare these temperatures and residence times with those mandated by the foregoing equations. If these temperatures and/or residence times are not within the ranges indicated by the foregoing equations, either temperature or residence time or both are modified to bring these characteristics within the ranges defined by the foregoing equations to thereby optimize selectivity. In the design and construction of new pyrolysis zone equipment, the configuration of the zone is selected so that the temperatures and residence times are within the preferred or especially preferred ranges.

The pyrolysis can be conducted catalytically or non-catalytically. Suitable catalysts include activated alumina, vanadia, molybdena, magnesia, alkaline earth pyrophosphates, zinc oxide, cobalt molybdate and the like. These catalysts can be used as such or supported on suitable inert carriers such as alumina, magnesia, silicon carbide, etc. As in other processes, use of catalysts facilitates obtention of faster rates of reaction at lower temperatures. But in view of the increased process complexity introduced

5 by use of catalysts and the high selectivities obtained in the absence of catalysts, the use of catalysts is not normally preferred.

10 The configuration of the pyrolysis zone itself is not of substantial importance to this invention and any convenient type can be employed. Thus, for example, one or a plurality of pyrolysis zones connected in series or in parallel or both can be employed. The pyrolysis zone itself can be in the form of a furnace with the feedstock flowing through the tubes thereof or it can be in the form of a shell-and-tube heat exchanger with the feedstock flowing through either the shell or the tube side thereof. The heating medium employed in the pyrolysis zone is equally of no significance to this invention. Hot gas (e.g., 15 combustion products) can be employed as can molten salt or other suitable high temperature media. Whatever form of pyrolysis zone is adopted, however, it is advantageous to minimize local overheating therein. Since the pyrolysis reaction itself is endothermic, although only slightly so (7000-7500 cal. per gram mole of ethylene glycol diacetate pyrolyzed) and thus requires heat input, the point at which such local overheating is most likely to occur is at the wall of the pyrolysis zone in contact with the feedstock, especially at points nearer to the outlet thereof. It is therefore desirable though not essential, to so configure the pyrolysis zone that the skin temperature is not more than 25° C. higher than the bulk temperature of the feedstock flowing through the pyrolysis zone and preferably not more than about 15° C. higher than this bulk temperature.

20 As used throughout this specification and in the claims, the phraseology "bulk temperature" is intended as synonymous with the so-called "mixing-cup temperature;" see Jakob, "Heat Transfer," vol. I, p. 422 et seq., J. Wiley, 25 New York (1959). Throughout this specification and in the claims, temperatures referred to are bulk temperatures unless otherwise stated.

30 It will readily be appreciated that the process of this invention is especially suitable for large-scale continuous commercial operation although batch or semi-batch operations are also possible.

35 Once the pyrolysis is completed, the pyrolysis zone effluent is cooled and vinyl acetate is separated therefrom in conventional manner as, for example, by fractionation. 40 As hereinabove indicated, unconverted feedstock can be recycled to the pyrolysis zone. The manner in which the pyrolysis zone effluent is cooled does not appear to be a critical factor to optimal vinyl acetate yields. Thus, cooling may be by rapid quenching with water or other relatively stable media or by such inherently slow techniques as heat exchange between pyrolysis zone effluent and pyrolysis zone feed.

EXAMPLES

45 The following examples are presented to further illustrate this invention but are not intended as limiting the scope thereof. Unless otherwise stated, all parts and percents in the following examples are on a molar basis and the following terms have the meanings indicated.

50 "Conversion"—the ratio (expressed as a percent) of:

55 $\frac{\text{Moles ethylene glycol diacetate reacting}}{\text{Moles ethylene glycol diacetate fed}}$

60 "Selectivity"—the ratio (expressed as a percent) of:

65 $\frac{\text{Moles vinyl acetate formed}}{\text{Moles ethylene glycol diacetate reacting}}$

70 "Yield"—the ratio (expressed as a percent) of:

75 $\frac{\text{Moles vinyl acetate formed}}{\text{Moles ethylene glycol diacetate fed}}$

Example I

Ethylene glycol diacetate is prepared by refluxing ethyl-

ene glycol and excess acetic acid in the presence of 1% (wt. basis) p-toluene sulfonic acid as a catalyst at atmospheric pressure until water liberation ceases (approximately 4 hours). During this operation, make-up acetic acid is periodically added to replace that lost with the water removed. The resultant material is then vacuum distilled to remove unreacted acetic acid, ethylene glycol and by-product ethylene glycol monoacetate and then re-distilled under vacuum to produce a dry ethylene glycol diacetate feed of 99% purity, the principal impurity being ethylene glycol monoacetate.

This feedstock is then charged as a liquid to an electrically heated 1 inch diameter steel tube which acts as a vaporizer. To facilitate heat transfer, this tube is packed with glass beads. The now-vaporized ethylene glycol diacetate is then passed to one of two differently configured pyrolysis zones denominated in the following table as reactor A and B. Reactor A is a 1 inch outer diameter, 13 BWG tube, 4 ft. in length to which heat is supplied by circulating molten salt through a jacket surrounding the tube. Reactor B is an unpacked $\frac{1}{4}$ inch outer diameter, 20 BWG tube 20 ft. in length shaped into a spiral and totally immersed in a constant temperature molten salt bath. The series of runs described in the following table are carried out at a varying mass velocity of ethylene glycol diacetate within the pyrolysis zone but with a constant pyrolysis zone inlet temperature of 500° C. and pressure of 50 p.s.i.g. (temperature maintained as necessary by bypassing cold ethylene glycol diacetate around the vaporized). Each run is continued for at least one-half hour or longer if necessary to attain steady-state operation. Pyrolysis zone effluents are analyzed by gas chromatography.

TABLE I

Run. No.	Reactor	Average temp., °C.	Time, sec.	Percent		Mass velocity, lbs./hr.ft. ²
				Conversion	Selectivity

10..... B		537	1.2	15	88	8,050

¹ Results are those reported by Shibahara et al., Technol. Reports, Osaka University, 11, No. 482 (1961) page 405.

² Results are those reported by Chitwood in U.S. Patent No. 2,251,983.

³ Mass velocity refers to lbs. per hour of contained ethylene glycol per sq. foot of pyrolysis zone cross-sectional area.

The lettered runs of the above table are controls, not illustrative of the invention. The results of the numbered runs tabulated above, which are illustrative of the invention, indicate that as mass velocity increases, selectivity also increases (albeit slightly) until, at about a mass velocity of ca. 1,000 (contrast runs 1, 4 and 9) it tends to level off and remain at a high level as mass velocity is further increased.

When runs similar to those described above are carried out at higher mass velocities, comparable results are obtained. For example, a run at a mass velocity of 20,000 lbs./hr./ft.² at 511° C. for a residence time of 10 seconds displays a conversion of 35% and a selectivity of 85%. A similar run at a mass velocity of 80,000 lbs./hr./ft.² at 520° C. for 2.3 seconds displays a 12% conversion and a selectivity of 92%. Other runs at 546° C. with mass velocities of 200,000 (time of one second) and 500,000

lbs./hr./ft.² (time of 0.4 second) give conversions of 15% and 10% respectively and respective selectivities of 92% and 95%.

Example II

5 Runs 4, 7 and 10 of Example I are repeated employing ethylene glycol diacetate prepared by reacting ethylene dichloride and sodium acetate according to the procedure of Shibahara et al., Technol. Repts., Osaka University, 11, No. 482, p. 405 (1961) and also by the reaction at 100° C. for 3 hours of glacial acetic acid and ethylene in the presence of palladous nitrate, sodium nitrate and cupric acetate (see Example 3 of British Pat. No. 1,124,862). In both instances the distillation procedures of Example I are followed to produce feeds of comparable ethylene glycol diacetate purity. Pyrolysis results are substantially identical. This indicates that the process of this invention is applicable to ethylene glycol diacetate feeds of any source.

These runs are also repeated with ethylene glycol diacetate prepared as in Example I to which is added varying amounts of halogenated compounds (an equimolar mixture of bromohydrin, ethylene dibromide, ethylidene dibromide and ethylene glycol bromoacetate or an equimolar mixture of the chlorine analogues of these materials). When 1% (wt. basis) of either mixture is added, a significant decrease in selectivity is noted. When only 20 p.p.m. are added, the selectivity decrease is of the order of 4-5% which is often acceptable. With 2 p.p.m. added, the selectivity decrease appears to be under 1% while no significant selectivity decrease is noted when lesser amounts are added.

Example III

A series of runs are carried out in a 1 inch outer diameter (15 BWG) steel tube of 80 feet length. The tube is shaped into a coil and completely submerged in a constant temperature salt bath. Feed material is preheated and vaporized prior to being fed to the reactor in a vaporizer similar to that described in Example I. Reactor off-gas is analyzed by gas chromatography. Those runs identified by number are illustrative of this invention since the time-temperature characteristics are within the parameters set forth above while lettered runs fall outside of these ranges and illustrate the somewhat poorer results obtained.

Run. No.	Temp., °C.	Res. time, sec.	Mass velocity, lbs./hr.ft. ²	Percent	
				Conversion	Selectivity
C.....	470	5	39,550	3.5	98.9
D.....	470	200	992	75.8	60.0
1.....	470	10	19,340	7.0	97.8
2.....	470	30	6,610	19.2	93.4
3.....	470	60	3,300	34.7	87.0
4.....	470	100	1,984	50.9	78.8
E.....	500	50	3,960	73.0	57.2
5.....	500	3	66,100	8.0	97.0
6.....	500	6	33,000	14.6	94.2
7.....	500	10	19,340	23.1	90.4
8.....	500	30	6,610	54.5	72.7
F.....	530	20	9,920	82.7	40.4
9.....	530	3	66,100	23.2	58.7
10.....	530	5	39,550	35.5	81.8
11.....	530	10	19,840	58.4	65.5

60 It will be noted that selectivity obtained in control C is quite high but the conversion in this control is so low as to render such a process normally uneconomic except in special situations.

Example IV

Runs 4, 7 and 10 of Example I are again repeated but at inlet pressures of 20 p.s.i.g., 50 p.s.i.g. and 200 p.s.i.g. In the runs at 200 p.s.i.g., vaporization of the ethylene is facilitated by admixing 10%, 20% and 50% of acetic acid with the ethylene glycol diacetate. The runs at 200 p.s.i.g. are also repeated employing sufficient nitrogen bubbled through the ethylene glycol diacetate feed to produce vapor admixtures of the same overall compositions. Results in all these runs are substantially similar to the corresponding runs of Example I.

Example V

A feedstock consisting essentially of ethylene glycol diacetate is prepared according to the teachings of Belgian Pat. No. 738,104 by continuously reacting ethylene, oxygen and acetic acid in the presence of tellurium added to the system in the form of tellurium dioxide and a bromide added to the system as HBr and fractionating the reaction effluent to produce a material of the following approximate composition:

Ethylene glycol monoacetate . 1%.
 Ethylene glycol diacetate --- 99%.
 Ethylene glycol ----- Trace.
 Diethylene glycol ----- <10 p.p.m. (wt. basis).

Small amounts (ca. 20 p.p.m.) of brominated impurities are also present and include bromohydrin, 2-bromoethanol and diethylene glycol di- and mono-bromides. This stream is continuously fed to a vaporizer at a rate of 5.90 parts per hour. Also fed to the vaporizer are 26.0 parts per hour of a recycle stream obtained as subsequently described which has the following composition:

Acetic acid -----	percent	6.07
Ethylene glycol monoacetate -----	do	0.33
Ethylene glycol diacetate -----	do	92.61
Vinyl acetate -----	do	0.16
Acetic anhydride -----	do	0.71
High boiling materials -----	do	0.12
Ketene -----	(¹)	
Acetone -----	(¹)	
Acetaldehyde -----	(¹)	
Diethylene glycol -----	(¹)	

¹ 180 p.p.m. (wt. basis).

The admixture formed by mixing the feedstock and recycle streams is vaporized at 60 p.s.i.a. and 225° C., pre-heated by indirect heat exchange with pyrolysis zone effluent to a temperature of 465° C. and then fed to the pyrolysis zone. The pyrolysis zone is in the form of a furnace through which the admixture flows at a mass velocity of 106,500 lbs./hr./ft.² of pyrolysis zone cross-sectional area (i.e., furnace tube cross-sectional area). During pyrolysis, the admixture is heated to 535° C. and the residence time within the pyrolysis zone is 2.1 seconds. The pyrolysis zone is arranged so that inner tube wall temperature is not more than 10° C. higher than bulk stream temperature toward the hot (outlet) end of the pyrolysis zone. The effluent from the pyrolysis zone (37.89 parts/hr.) has the following approximate composition:

	Percent
Acetic acid -----	21.11
Vinyl acetate -----	13.52
Ethylene glycol monoacetate -----	0.28
Acetone -----	0.64
Acetaldehyde -----	0.03
Acetic anhydride -----	0.59
Carbon monoxide -----	0.64
Ketene -----	0.03
High boiling materials -----	0.01
Low boiling materials -----	0.62
Ethylene glycol diacetate (unreacted) -----	62.44
100.00	

The pyrolysis zone effluent also includes small quantities of higher glycols (di- and triethylene glycol) as well as small amounts of brominated hydrocarbons (e.g., bromohydrin, ethylene dibromide and ethylidene dibromide) as well as other materials such as ethylidene diacetate. This effluent is cooled to 316° C. by heat exchange with the pyrolysis zone feed and, now at a pressure of 40 p.s.i.a., is further cooled to 160° C. prior to treatment for product recovery.

Product recovery is accomplished by a sequence of distillations wherein low-boiling materials (including unidentified low-boiling materials and carbon oxides) are first removed. Then, in a subsequent distillation, materials boiling at a higher temperature than vinyl acetate are removed as a bottoms product and recycled by pyrolysis zone feed. This bottoms is the source of the recycle stream admixed with the feedstock to pyrolysis. The overhead, containing the vinyl acetate, is distilled to remove light materials, predominately acetone and heavy materials such as acetic acid. Vinyl acetate product of greater than 99% purity (5.08 parts/hr.) is obtained. Acetic acid by-product can, of course, be used to prepare additional ethylene glycol diacetate containing feedstock. Acetone, the principal product of side reactions, may also be purified and sold.

From the foregoing, it will be noted that ethylene glycol diacetate conversion across the pyrolysis zone itself is approximately 19.5% per pass, selectivity across the pyrolysis zone is over 89.5% per pass, which also represents overall yield, neglecting losses in recovery.

In a similar operation the foregoing example is repeated except that wall temperature is increased by adjusting heating rate so that wall temperature in the pyrolysis zone is as much as 40° C. higher than bulk stream temperature. Conversion increases slightly to about 21% per pass but selectivity falls to about 86%. Additionally later examination of the pyrolysis zone indicates deposition of carbonaceous materials on the wall thereof.

What is claimed is:

1. In a process for the vapor phase pyrolysis of a feedstock consisting essentially of ethylene glycol diacetate to vinyl acetate, the improvement which comprises pyrolyzing the feedstock within a pyrolysis zone wherein the pyrolysis is conducted at a temperature between about 435° C. and about 560° C. for a residence time of the feedstock within the pyrolysis zone from about 0.1 second to about 200 seconds, the feedstock mass velocity being at least 200 lbs./hr./ft.² of pyrolysis zone cross-sectional area.

2. In a process for the vapor phase pyrolysis of a feedstock consisting essentially of ethylene glycol diacetate to vinyl acetate, the improvement which comprises forcing the feedstock through a pyrolysis zone at a mass velocity of at least 200 lbs./hr./ft.² of pyrolysis zone cross-sectional area by means of a pressure differential between pyrolysis zone inlet and outlet pressures while supplying external heat to the surface of the pyrolysis zone in contact with the material being forced through the pyrolysis zone and conducting the pyrolysis at a temperature between about 435° C. and about 560° C. for a residence time between about 0.1 second and about 200 seconds, the difference between the temperature of the surface of the pyrolysis zone in contact with the material being forced through the pyrolysis zone and the bulk fluid temperature within the pyrolysis zone not exceeding 25° C.

3. A process in accordance with claim 2 wherein the temperature difference is not greater than 15° C.

4. A process in accordance with claim 2 wherein the pressure differential between pyrolysis zone inlet and outlet pressures is between about 0.5 p.s.i. and about 65 p.s.i.

5. A process in accordance with claim 2 wherein the pressure differential between pyrolysis zone inlet and outlet pressures is between about 0.5 p.s.i. and about 65 p.s.i. and the temperature difference is not greater than 15° C.

6. A process in accordance with claim 1 wherein the feedstock contains at least 70 mole percent ethylene glycol diacetate and not more than 200 p.p.m. (wt. basis) of halogenated impurities.

7. A process in accordance with claim 6 wherein the feedstock contains less than 20 p.p.m. of halogenated impurities.

8. A process in accordance with claim 1 wherein the mass velocity is at least 250 lbs./hr./ft.².

9. A process in accordance with claim 1 wherein the mass velocity is at least 300 lbs./hr./ft.².

10. A process in accordance with claim 1 wherein the mass velocity does not exceed 500,000 lbs./hr./ft.².

11. A process in accordance with claim 1 wherein the mass velocity is between about 250 and about 300,000 lbs./hr./ft.².

12. A process in accordance with claim 1 wherein the mass velocity is between about 300 and about 200,000 lbs./hr./ft.².

13. A process in accordance with claim 1 wherein the residence time within the pyrolysis zone is not less than a value such that

$$\ln \theta = \frac{27,940}{T} - 35.8273$$

and is not in excess of a value such that

$$\ln \theta = \frac{25,000}{T} - 28.8175$$

wherein ln is the symbol for the Napierian logarithm, θ is the residence time of the feedstock within the pyrolysis zone in seconds and T is the arithmetic average of pyrolysis zone inlet and outlet temperatures in degrees Kelvin.

14. A process in accordance with claim 13 wherein the residence time is not less than a value such that

$$\ln \theta = \frac{25,000}{T} - 31.7002$$

and is not in excess of a value such that

$$\ln \theta = \frac{25,000}{T} - 29.0945$$

θ not being in excess of 100 seconds and T being at least 718° K. but not above 823° K.

UNITED STATES PATENT OFFICE
CERTIFICATE OF CORRECTION

Patent No. 3,804,887 Dated April 16, 1974

Inventor(s) Robert Hoch et al.

It is certified that error appears in the above-identified patent and that said Letters Patent are hereby corrected as shown below:

Column 1, line 65, "lbs./hr.ft.²" should read -- lbs./hr. - ft.². --. Column 2, line 34, "The preferred" should read -- This preferred --. Column 4, line 49, "tiivty" should read -- tivity --. Column 7, line 23, "imemrsed" should read -- immersed. --; line 30, "vaporized)." should read -- vaporizer). --; column 7, Table I, second figure in "Average temp., °C." column reads "500." should read - 550 --. same table I, note 3 refers to "ethylene glycol per sq. foot" should read -- ethylene glycol diacetate per sq. foot. --. Column 9, line 61, the percent for high boiling materials is shown as "0.01" should read -- 0.10. --. Column 10, line 6, "recycled by pyrolysis" should read -- recycled to pyrolysis. --; line 34, "pyrolyz--" should read -- pyrolyzing. --.

Signed and sealed this 24th day of September 1974.
